CLAIM

The ornamental design for an electronic device or portion thereof with animated graphical user interface, as shown and described.

DESCRIPTION

FIG. 1 is a front view of an electronic device or portion thereof with animated graphical user interface showing our new design;

FIG. 2 is a second image thereof;

FIG. 3 is a third image thereof;

FIG. 4 is a fourth image thereof;

FIG. 5 is a fifth image thereof; and,

FIG. 6 is a sixth image thereof.

The peripheral dashed broken lines illustrate a display screen or portion thereof, and form no part of the claimed design.

In FIGS. 3-6, the dashed broken line circles form part of the claimed design.

The appearance of the graphical user interface transitions between the images shown in FIGS. 1-6. The process or period in which one image transitions to another forms no part of the claimed design.
